Patented June 6, 1961

190,490

ELECTRIC HAIR CLIPPER

Alfred W. Madl, Milwaukee, Wis., assignor to John Oster
Manufacturing Co., Milwaukee, Wis., a corporation of
Wisconsin

Filed Nov. 17, 1960, Ser. No. 62,881

Term of patent 14 years

(Cl. D22—3)

Fig. 1.

Fig. 2.

Fig. 3.

Fig. 4.

Fig. 5.

FIGURE 1 is a front perspective view of an electric hair clipper, embodying my design;

FIGURE 2 is a rear perspective view thereof;

FIGURE 3 is a top plan view of the electric hair clipper;

FIGURE 4 is a bottom plan view thereof; and

FIGURE 5 is a side elevational view thereof.

The dominant features of my design reside in those portions thereof shown in full lines.

I claim:

The ornamental design for an electric hair clipper, as shown and described.
